GOLF PUTTER

Joseph P. Leone, 780 Danner St.,
Tallmadge, Ohio 44278

Filed Dec. 4, 1969, Ser. No. 20,359

Term of patent 14 years

Int. Cl. D21—03

U.S. Cl. D34—5

FIG. 1 is a front elevational view of a golf putter showing my new design;

FIG. 2 is a right side elevation of the putter of FIG. 1;

FIG. 3 is a left side elevation of the putter of FIG. 1;

FIG. 4 is a bottom plan of the putter, and

FIG. 5 is a horizontal section taken on lines 5-5 of FIG. 4.

The shaft has been omitted from FIGS. 2, 3, 4 and 5 for convenience of illustration.

I claim:

The ornamental design for a golf putter, as shown and described.
